UNITED STATES PATENT OFFICE.

FRED A. RAHFELDT, OF ZEARING, IOWA.

HARNESS-VISE.

1,253,725.

Specification of Letters Patent. Patented Jan. 15, 1918.

Application filed July 2, 1917. Serial No. 178,207.

To all whom it may concern:

Be it known that I, FRED A. RAHFELDT, a citizen of the United States, residing at Zearing, in the county of Story, State of Iowa, have invented certain new and useful Improvements in Harness-Vises; and I do hereby declare the following to be a full, clear, and exact description of the invention, such as will enable others skilled in the art to which it appertains to make and use the same.

This invention is an improvement in vises and has particular reference to a harness vise.

An object of the invention is to provide an improved apparatus for clamping harness or other leather articles in position for sewing the same and, to this end, use is made of a pair of clamping members having associated therewith an adjusting device for operating said members to clamp the article to be sewed, said adjusting device being retained in adjusted position by a latch which is released through the medium of a trip carried by one of said jaws whereby to permit the same to return to their normal positions.

Another object is to provide an apparatus of this character which is simple in construction, easy to manufacture and effective in carrying out the purpose for which it is designed.

The inventive idea involved is capable of receiving a variety of mechanical expressions, one of which, for the purpose of illustrating the invention, is shown in the accompanying drawing, wherein:—

Figure 1 is an end elevation of the device showing the clamping members in inoperative position.

Fig. 2 is a similar view showing the clamping members in operative position.

Fig. 3 is a side elevation.

Fig. 4 is a horizontal sectional view.

Referring more particularly to the drawing, the numeral 5 indicates a base to which is hinged at 6 an upwardly inclined clamping member 7. Also fixed to the base is a second inclined clamping member 7' converging toward the first-named member and said members have the coöperating jaws 8 at their upper ends which are normally held in spaced or inoperative relation by a coil spring 9 interposed between said members. A support for the member 7' is pro-

vided in the form of a brace 9' secured thereto and to the base 5.

The means for adjusting the member 7 to clamping or operative position preferably comprises a flexible strap 10 extending through openings 11 adjacent the upper ends of said members and secured at one end to the member 7. The other end of the strap is extended forwardly and is fastened at 12 to a foot treadle 13 which is pivoted at 14 to the adjacent clamping member 7' so that when the treadle 13 is depressed the strap 10 will be drawn downwardly and thus adjust the jaws 8 toward each other against the tension of the spring 9.

Means are provided for releasably retaining the treadle 13 in its depressed position; and these means preferably comprise a latch or pawl 15 pivoted at 16 to the clamping member 7' to which the treadle 13 is pivoted and having its free end adapted for engagement with the rack teeth 17 formed upon the treadle 13 so that when the latter is depressed said latch will retain the same in such position until released.

A trip arm 18 is pivoted at 19 to the opposite clamping member 7 adjacent its lower end and extends transversely of said clamping members and has one end thereof arranged in juxtaposition to the latch 15 and normally held out of contact therewith by a coil spring 20 secured to the base 5 and to said arm 18. The opposite end of the trip arm is curved to provide a foot pedal 21 which is adapted to be depressed to adjust the opposite end of the arm 18 upwardly and in contact with the latch 15 whereby to disengage the same from the rack 17, and upon the release of the treadle 13 the spring 9 will operate to force the clamping members 7 and 7' apart.

What is claimed is:—

1. A vise of the class described, comprising a base, a pair of upwardly converging clamping members associated therewith, a strap secured to one of said members, a treadle pivoted to one of said members and connected to said strap whereby to adjust the clamping members to clamping position when said treadle is depressed, rack teeth formed upon said treadle, a latch pivoted to one of said clamping members and engageable with said teeth to retain said treadle in depressed position, and a trip pivoted to the other clamping member and

engageable with said latch to release the same from engagement with said teeth whereby to permit of a return of the clamping members to inoperative position.

- 5 2. A vise of the class described, comprising a base, a pair of upwardly converging clamping members associated therewith, a strap secured to one of said members, a treadle pivoted to one of said members and 10 connected to said strap whereby to adjust the clamping members to clamping position when said treadle is depressed, rack teeth formed upon said treadle, a latch pivoted to one of said clamping members and engageable with said teeth to retain said 15

treadle in depressed position, and a trip pivoted to the other clamping member and engageable with said latch to release the same from engagement with said teeth whereby to permit of a return of the clamping members to inoperative position, and a spring extending between said clamping members for returning the same to inoperative position when said latch is released. 20

In testimony whereof, I affix my signature 25 in the presence of two witnesses.

FRED A. RAHFELDT.
